UNITED STATES PATENT OFFICE.

NATHAN S. BEARDSLEE, OF WARSAW, NEW YORK.

APPARATUS FOR THE MANUFACTURE OF SALT.

SPECIFICATION forming part of Letters Patent No. 320,207, dated June 16, 1885.

Application filed January 28, 1885. (Model.)

To all whom it may concern:

Be it known that I, NATHAN S. BEARDSLEE, a citizen of the United States, residing at Warsaw, in the county of Wyoming and State 5 of New York, have invented a new and useful Apparatus for the Manufacture of Salt, of which the following is a specification.

My invention relates to improvements in apparatus for the manufacture of salt, in 10 which artificial heat is used to aid the evaporation and release of the salt held in solution; and the objects of my improvements are, first, to provide a salt-grainer with heating-tubes, having a fire-box in one end of the tube, the 15 said tube being submerged in the brine; second, to afford facilities for automatically depositing the salt at the side of the grainer instead of at the end of the same; and, third, to reduce the friction of the rake by giving it 20 an oscillating movement by the rolling of a single longitudinal shaft. I attain these objects by the mechanism illustrated in the accompanying drawings, in which—

Figure 1 is a top plan view; Fig. 2 is a 25 cross-section taken through the grainer and one of the heating-tubes, showing the return-flue in said tube, and Fig. 3 is a front end view with the doors open showing the fire-box.

30 Similar letters refer to similar parts throughout the several views.

A represents the grainer, made of any suitable material, semispherical in form, within which the brine is placed.

35 B is the furnace-front, to which are hinged the furnace-doors b.

C are longitudinal tubes of large diameter, secured to the furnace-front and end walls of the grainer and extending the entire length 40 of the same. These tubes may be provided with a center longitudinal wall, J, with the smoke-pipe at the front so as to form a return-flue for the utilizing of the entire heat, or the tube alone may be used with the smoke-exit 45 pipe at the rear end and remote from the fire-chamber.

e are fire-grates secured centrally within each tube at the front ends thereof; D are the smoke-exit pipes, one to each tube.

50 E is a longitudinal shaft, carrying the arms F, upon the outer ends of which are secured

the circular bands F'. Upon the peripheral edge of these circular bands are hinged the scrapers G.

g are brackets made fast to bands F' upon 55 the periphery of the same, and against which the scrapers rest when moving in the direction necessary for the removal of the salt. It will be observed that the scrapers being hinged to the circular bands they will follow in the line 60 of the revolution of the same one way, and will only elevate the salt through the intervention of the brackets against which the scrapers rest. For depositing upon both sides 65 duplicate scrapers and brackets are used.

H are bearing-boxes secured to either end of the grainer and within which the shaft E turns.

I is a crank-arm attached to the shaft E at a point outside of the grainer, and to which 70 the operating-power is applied.

In practice the grainer or brine-heating receptacle is of some considerable length. The heating-tubes are of large enough diameter to allow of the requisite fuel space in one end of 75 the tube, the said tube extending the required length of the grainer and being submerged in the brine. These tubes are of the required number, (from two to six,) and are accessible for the removal of incrustations which form upon 80 the outside of all metal heating-pipes that pass through hot brine. When a great length of grainer is used, the heat may become fully utilized without the employment of the return-flue, as shown at J, Fig. 2; but I prefer 85 the substitution of the return-flue on the score of economy.

I am aware that prior to my invention salt-grainers have been used having heating-pipes and the same made to run longitudinally 90 through the grainer; but as far as I am aware I am the first to organize a heating-tube that has a fire-box in one end, or that has a central dividing-wall for forming a return-flue, and thus combining in a single tube a fire-box, a 95 heating-tube, and a return-flue.

Having now described my invention, what I claim as new, and desire to secure by Letters Patent, is—

1. In a salt-evaporator, the longitudinal 100 heating-tube submerged within the brine, the central longitudinal dividing-wall within the

tube for forming one single direct and one single return flue, the fire-box located in the front end of one sub-division of the tube, the smoke exit pipe connecting with the other subdivision, all combined with the grainer, and operating substantially as described.

2. The semicircular grainer carrying the oscillating rake-frame, and the hinged scrapers, rigid when at work and flexible when idle, in combination with a periodic operating mechanism, and arranged for the automatic lateral depositing of the salt, substantially as herein described and set forth.

3. The combination of the longitudinal shaft E, arms F, circular bands F', and scrapers G, said scrapers being rigidly supported when in working position and flexibly following in line of movement when idle, and arranged in such manner that the salt may be raked from underneath the heating-tubes and deposited at the side of the grainer, substantially as described.

NATHAN S. BEARDSLEE.
